UNITED STATES PATENT OFFICE.

WILLIAM E. BERTRAM, OF BROOKLYN, NEW YORK, ASSIGNOR TO INTERNATIONAL
TYPESETTING MACHINE COMPANY, OF NEW YORK, N. Y., A CORPORATION OF NEW
YORK.

LINOTYPE-MACHINE.

1,168,243.

Specification of Letters Patent. Patented Jan. 11, 1916.

Application filed July 5, 1912. Serial No. 707,930.

To all whom it may concern:

Be it known that I, WILLIAM E. BERTRAM, a citizen of the United States, residing at Brooklyn, in the county of Kings and State of New York, have invented new and useful 5 Improvements in Linotype-Machines, of which the following is a specification.

The present invention relates to improvements in linotype machines employing a 10 magazine to contain the stored matrices and escapement mechanism for controlling the delivery of matrices therefrom as required, and the primary objects of this invention are to provide an improved construction which 15 enables the magazine to be removed readily and another to be applied without disturbing the escapement mechanism, and moreover, a continuous or unbroken passageway for the matrices past the escapement is provided, thus avoiding retarding or stopping 20 of the matrices, and to provide simple and improved means for locking the matrices at the mouth or delivery end of the magazine and for preventing spilling of the matrices 25 from the receiving end of the magazine when the magazine is removed from the machine and is being handled, as for example during interchanging of the magazines.

To these and other ends, the invention 30 consists in certain improvements, and combinations and arrangements of parts, all as will be hereinafter more fully described, the novel features being pointed out particularly in the claims at the end of the specification.

In the accompanying drawing: Figure 1 is a perspective view of a matrix adapted to be used in connection with the matrix-retaining or locking means provided by the 35 present invention; Fig. 2 is a perspective view of a magazine embodying the present invention; Figs. 3 and 4 show the upper portion or matrix-receiving end of the magazine equipped with a rail which serves to prevent spilling of the matrices from this end of the 40 magazine; Fig. 5 shows the lower or delivery end of the magazine and the coöperative escapement mechanism, the matrices being locked in the magazine; Fig. 6 shows the mouth or delivery end of the magazine, partly in plan and partly in section, illustrating the manner in which the matrices 45 are locked; Fig. 7 is a view similar to Fig. 5, but showing the lower section of the magazine swung into inoperative relation to the escapement mechanism preparatory to re-

moval of the magazine from the machine; Fig. 8 is a view similar to Fig. 7 showing a modified construction.

Similar parts are designated by the same reference characters in the several views.

In linotype machines as heretofore constructed with a removable magazine formed separately from the escapement mechanism, it has been the practice to so arrange the escapement that the matrix-engaging parts 60 thereof project upwardly through openings in the magazine, the escapement mechanism forming only a small portion of the matrix channel, and in those constructions, the passageway for the matrices is interrupted or 65 broken and imperfections of fit, due to imperfect workmanship or wear, it has been found, produce shoulders or obstructions which retard or stop the matrices, thus interfering with the proper delivery of the 70 matrices from the magazine. The present invention obviates the objections which have been experienced with linotype machines of this type as heretofore constructed and provides a generally improved construction 75 80 whereby delivery of the matrices is insured, and moreover, the removal of one magazine from the machine and the substitution of another may be accomplished quickly and with facility.

The preferred embodiments of the invention are shown in the accompanying drawing and will be hereinafter described in detail, but it is to be understood that the invention is not restricted to the particular constructions shown, as equivalent constructions may 90 be used in carrying the invention into practice.

In the present instance, the magazine having the channels in which the matrices are 95 stored is composed of two sections, an upper section 1 and a lower section 2, the matrices being received by the upper end of the section 1 from the distributing mechanism, and the matrices being delivered from the lower 100 section 2 under the control of the escapement mechanism. In the construction shown in Figs. 2, and 5-7 inclusive, the lower section 2 is movably connected or related to the upper section, a pair of hinges 3 being shown 105 in the present instance which pivotally connect the magazine sections and permit the lower section 2 to be moved to and from an operative position with respect to the escapement mechanism while the upper section of 110

the magazine remains stationary with respect to the machine. The top and bottom walls of the magazine are formed as usual with the matrix-guiding channels 4, the 5 channels of the two magazine sections being continuous.

Escapement mechanisms of different kinds may be used in connection with the present improvements, a conventional type of escapement mechanism being shown for example in the present instance which embodies the member 5 which is pivoted to rock on a pin 6 and coöperates with the upper and lower matrix-controlling pawls 7 and 8, a spring 9 acting on the escapement to normally retain the pawl 8 in position to prevent delivery of the lowermost matrix in the respective magazine channel, and a reed 10 which may be actuated as usual from the keyboard mechanism serves to operate the escapement to cause delivery of the matrices as required. The escapement mechanism, however, according to the present invention embodies a plate 11 which is in fixed relation 15 to the escapements and to the machine frame, as compared with the magazine which is removable with respect to the machine. This plate 11 forms a continuation of the bottom 12 of the magazine when the latter is in 20 operative position, and said plate is provided on its upper face with matrix-guiding grooves 13 which are continuations of those formed in the bottom of the magazine. As shown in Figs. 5 and 7, the hinged or movable lower section 2 of the magazine has a bottom portion 14 which, when the magazine is in operative position, serves to form an uninterrupted or unbroken passageway between the bottom 12 of the upper section 25 of the magazine and the stationary plate 11 of the escapement mechanism, and in order to permit the lower magazine section 2 to be swung from an operative position as shown in Fig. 5 to an inoperative position 30 as shown in Fig. 7 about the hinge 3 as an axis, and to also avoid catching of the matrices upon the joint between the bottom 14 of the magazine section 2 and the plate 11, the meeting edges of the bottom 14 and the plate 35 11 are preferably beveled or inclined toward the direction of movement of the matrices as shown at 15. By providing a plate such as that shown at 11 and which is stationary with respect to the escapement mechanism, 40 the matrix-controlling pawls 7 and 8 of each escapement may extend upwardly into the matrix-guiding channels 13 of the plate without requiring recessing or cutting away of the side walls, these channels thus avoiding the formation of shoulders or obstructions which might tend to retard or check the movement of the matrices and cause 45 faulty delivery.

As the plate 11 forms the bottom of the 50 lower magazine section 2 while the latter is

in operative position, means is provided for locking or holding the matrices in the lower section of the magazine when the same is moved from its operative position. Preferably, the matrices are provided with transverse openings 16 which extend through the bodies thereof, and the side walls 17 and 18 of the lower magazine section 2 are provided with pairs of apertures 19 and 20, the apertures in the lowermost row of matrices 55 registering substantially with the apertures 19 in the side walls of the lower magazine section while the apertures in the following or next higher row of matrices register substantially with the apertures 20 in said magazine section, when the parts are in normal position. To lock the matrices in the lower magazine section, a pair of locking pins 21 and 22 are preferably used, these pins being adapted for insertion through 60 the apertured side walls of the lower magazine section and the apertures in the corresponding rows of matrices as shown diagrammatically in Fig. 6. In order to facilitate removal of the magazine from the 65 machine, means is provided for holding the lower magazine section, with the matrices locked therein, in inoperative relation to the escapement mechanism preparatory to the removal of the magazine. 70 In the present instance, a locking bar 23 is provided at the side of the magazine, that shown being slotted longitudinally and provided with pins 24 which guide the bar longitudinally and secure it to the upper magazine section, and this bar has a bevel 25 which, when the locking bar is shifted in a direction toward the lower magazine section 2, engages one of the matrix-locking pins, (the pin 22 in the present instance) 75 and thereby supports the lower magazine section 2 in inoperative position above the escapement mechanism and in tilted relation to the upper magazine section. A reversible pawl 26 is preferably pivoted to 80 the upper magazine section 1 at 27 and is adapted to coöperate with a notch 28 in the bar 23 to retain the latter in engagement with the matrix-retaining pin 22, another notch 29 on the bar coöperating with 85 the pawl 26 to retain the bar in inoperative position as shown in Fig. 2.

After the matrices in the lower magazine section have been locked therein and said section has been shifted from its operative 90 relation to the escapement mechanism, the magazine may then be removed bodily from the machine. In order, however, to prevent spilling of matrices from the upper or receiving end of the magazine, should the 95 magazine be inverted, a matrix-retaining rail is provided, the rail 30 shown in the present instance being provided at its ends with arms 31 which are connected to the 100 opposite sides of the upper magazine section 105 110 115 120 125 130

1 by the pivots 32; and the rail in the present instance is capable of performing two functions, that is to say, when it occupies one position, its lower face 33 will serve as a guide to direct the matrices into 5 their appropriate channels in the magazine, and when the rail occupies another position, the surface 34 thereon will coöperate with the matrices in the magazine to prevent 10 discharge thereof from this end of the magazine. Devices are provided for retaining the rail in either of said positions as desired, a pair of catches 35 being provided in the 15 present instance which may be pivoted to the upper side of the magazine section 1, and these catches are adapted to coöperate with a pair of lugs or projections 36 on the rail, the catches engaging the under sides of these lugs or projections as shown in Fig. 3 when 20 the rail occupies a position to guide the matrices into the magazine and engaging the upper sides of said lugs to retain the rail in position to prevent spilling of the matrices from the upper or receiving end of 25 the magazine. By using a matrix-retaining rail at the upper or receiving end of the magazine in connection with the matrix-locking devices at the lower or delivery end of the magazine, it is obvious that the magazines may be handled more easily than heretofore and without danger of spilling of 30 matrices therefrom.

In Fig. 8, a somewhat modified form of the invention is shown, the magazine being formed substantially as one section 37 having the matrix-guiding channels formed as usual in the top and bottom thereof, and the bottom of the magazine is cut away adjacent to the delivery end of the magazine to accommodate a plate 38 which occupies a fixed 40 relation to the escapement mechanism, the plate 38, when the magazine is in position, serving as a continuation of the bottom of the magazine and is formed with channels 45 which constitute continuations of the matrix-guiding channels in the bottom of the magazine. The escapement 39 shown is formed in one piece, it being pivoted at 40 to the lug 41 at the under side of the plate 50 38, and the escapement has pawls or matrix-controlling projections 42 and 43 which project into the respective matrix-guiding channel in the plate 38 to control the delivery of matrices from the magazine in the well-known manner. These pawls 42 and 43 of the escapement, however, are so positioned that the lowermost row of matrices 44 will be arrested by the escapement at a point where the bottom 45 of the removable magazine will underlie and support the upper 55 ends of the matrices in this row, and when the locking bar 46 is inserted, it will lock the lowermost row of matrices in the magazine in such a manner that the magazine may be 60 instantly removed from the machine without 65

interfering with the escapements and another similarly constructed magazine may be readily applied, the lowermost row of matrices assuming at once a correct relation with the escapements.

70

What I claim is:—

1. In a linotype machine, the combination of a removable matrix magazine, and a relatively stationary escapement mechanism separable from but forming a part of the magazine when in operative position, from a point above the escapement mechanism to the discharge end of the magazine.

75

2. In a linotype machine, the combination of a removable matrix magazine, and a relatively stationary matrix-controlling escapement mechanism coöperative therewith and embodying a plate separable from the magazine and forming an uninterrupted matrix guide past the escapement mechanism when the magazine is in operative position.

80

3. In a linotype machine, the combination of a removable matrix magazine having a channeled bottom for guiding the matrices, and a relatively stationary escapement mechanism embodying a plate channeled to form an uninterrupted continuation of the channeled bottom of the magazine past the escapement mechanism.

85

4. In a linotype machine, the combination of a matrix magazine having a channeled matrix-guiding bottom a portion of which is cut away adjacent to the delivery mouth of the magazine, and escapement mechanism embodying a plate adapted to removably fit 100 said cut-away portion of the magazine bottom and forming an uninterrupted continuation of the magazine bottom past the escapement mechanism, and means for preventing spilling of matrices endwise and dropping of 105 matrices from the cut-away portion of the magazine when the latter is removed from the escapement mechanism.

95

5. In a linotype machine, the combination of matrix-controlling escapement mechanism, and a magazine bodily removable with respect thereto and embodying a section movable relatively to the body of the magazine to disengage the matrices in said section from the escapement mechanism.

110

6. In a linotype machine, the combination of matrix-controlling escapement mechanism, and a magazine bodily removable with respect thereto and embodying upper and lower sections, the lower section being shiftable relatively to the upper section to disengage the matrices therein from the escapement mechanism.

115

7. In a linotype machine, the combination of matrix-controlling escapement mechanism embodying a relatively stationary plate channeled to guide the matrices past the escapements, and a magazine embodying movably connected sections, one of said sections having a cut-away portion to receive said 120

125

130

plate and being shiftable relatively to said plate and the other magazine section to disengage the matrices from the escapement mechanism.

5. 8. In a linotype machine, the combination of matrix-controlling escapement mechanism, and a removable magazine embodying sections one of which is shiftable relatively to the other to disengage the matrices from the escapement mechanism, and means for holding said sections in shifted relation.

9. In a linotype machine, the combination of a matrix magazine having its bottom cut-away adjacent to the delivery end thereof, 15 matrices having apertures extending transversely therethrough, and a removable locking rod adapted for insertion through said apertures in the matrices and coöperative with the magazine to support and lock the matrices opposite to the cut-away portion of the magazine.

10. In a linotype machine, the combination of a matrix magazine embodying movably connected sections, means for locking the matrices in the magazine, and means controlled by said matrix-locking means for holding the magazine sections in inoperative relation.

11. In a linotype machine, the combination of relatively stationary escapement

mechanism, a matrix magazine embodying relatively shiftable sections one of which serves to carry the matrices to and from operative relation with respect to the escapement mechanism, means for locking the 35 matrices in the magazine, and means coöperative with said locking means for retaining one of the magazine sections in inoperative relation to the escapement mechanism. 40

12. The combination of a magazine for receiving and delivering matrices, a guard movably mounted at the matrix-receiving end of the magazine and having a portion to guide the matrices in entering the magazine when the guard occupies one position and an abutment portion to prevent spilling of the matrices when the guard occupies another position, the guard also having a projection, and a device arranged to engage the 50 opposite sides of said projection respectively to retain the guard in each of said positions.

In testimony whereof I have hereunto set my hand in presence of two subscribing witnesses.

WILLIAM E. BERTRAM.
